(57) **CLAIM**

The ornamental design for a food mashing device, as shown, and described.

DESCRIPTION

FIG. 1 is a perspective view of the food mashing device;
FIG. 2 is a front view of the food mashing device;
FIG. 3 is a rear view of the food mashing device;
FIG. 4 is a left side view of the food mashing device;
FIG. 5 is a right side view of the food mashing device;
FIG. 6 is a top view of the food mashing device; and,
FIG. 7 is a bottom view of the food mashing device.

The dashed lines illustrate a release button that forms no part of the claimed design.
